UNITED STATES PATENT OFFICE.

AUGUST WERNICKE, OF NEW YORK, N. Y.

COMBINED WRITING-DESK AND WORK-BOX.

SPECIFICATION forming part of Letters Patent No. 224,257, dated February 3, 1880.

Application filed June 12, 1879.

To all whom it may concern:

Be it known that I, AUGUST WERNICKE, of the city, county, and State of New York, have invented a new and Improved Combined 5 Writing-Desk and Work-Box, which invention is fully set forth in the following specification, reference being had to the accompanying drawings, in which—

Figure 1 represents a vertical cross-section 10 of my writing-desk and work-box when shut, the plane of section being indicated by the line *x x*, Fig. 3. Fig. 2 is a similar section thereof when open, the plane of section being indicated by the line *y y*, Fig. 3. Fig. 3 is a 15 plan or top view of the same.

Similar letters indicate corresponding parts.

This invention consists in a box having a hinged lid, a false bottom to such box having a less width or length than the space inclosed 20 by the box-walls, so that a space is left between one edge of said false bottom and one of said walls, a partition rising from the false bottom at its terminus above the sides of the box, a flexible desk-leaf fitted into the well 25 formed by the false bottom and partition, a guide-roller arranged in this well, and a stop acting on the desk-leaf, so organized that while the leaf may be shoved into the well mentioned, thereby laying bare the box and 30 adapting the same to the uses of a work-box, it is capable of being pulled out so as to allow its outer end to rest on one side of the box, whereby it is brought to an inclined position convenient for writing.

35 In the drawings, the letter A designates the box, and B its lid, attached thereto by means of hinge-joints *a*. C is the false bottom of the box, and D the partition. E is the desk-leaf.

40 The false bottom C is joined to the two ends and front wall, but does not reach to the rear wall of the box A, and in this example it terminates at such a distance from such wall as to make room for a stationery-compartment, 45 *b*, and at the same time leave sufficient room between this compartment and the partition D, situated at the end or terminus of the false bottom, for the passage of the desk-leaf E.

The partition D rises from the false bottom 50 C above the sides of the box A, and, together with the false bottom, serves to form an angular well, F, into which the desk-leaf E is fitted. This desk-leaf E is constructed of a

series of slats, *c*, attached to a cloth or other similar back, *d*, so that the leaf is flexible, the 55 outer slat being wider than the remainder and being provided with a ledge, *e*. In this example the leaf E is made of less width than the length or width of the box A, the object of this arrangement being to gain room for 60 pen-racks *f*, one on each side of the leaf, within the box.

In the vertical portion of the well F is arranged a roller, G, turning on a shaft, *g*, to guide the leaf E in its movements. A bevel, 65 *h*, formed on the lower part of a standard, serving to support the compartment *b*, also assists in guiding the leaf E.

On its opposite edges, and near its inner end, the leaf E is provided with a pin, *i*, which, 70 together with a cross-piece, *j*, arranged at each end of the well F, form stops to regulate the outer position of the leaf.

When it is desired to use the box A as a work-box the leaf E is shoved into the well 75 F, as shown in Fig. 1, and when a writing-desk is desired the leaf is drawn out, and its outer end permitted to rest on the front side of the box, as shown in Figs. 2 and 3. Inasmuch as the partition D is higher than the 80 sides of the box, the leaf E is inclined when brought to the position last named, and hence it forms a very convenient writing-desk.

What I claim as new, and desire to secure by Letters Patent, is—

85 A combined desk and work-box consisting of a box having a hinged lid, a false bottom to such box which has a less width or length than the space inclosed by the box-walls, so that a space is left between one edge of said 90 false bottom and one of said walls, a partition rising from the false bottom at its terminus above the sides of the box, a flexible desk-leaf fitted into the well formed by the false bottom and partition, a guide-roller arranged 95 in this well, and a stop acting on the desk-leaf, the whole organized and adapted for use substantially as described.

In testimony that I claim the foregoing I have hereunto set my hand and seal this 1st 100 day of March, 1879.

AUG. WERNICKE. [L. S.]
